UNITED STATES PATENT OFFICE.

EDWIN A. HALLAM, OF MACON, GEORGIA.

CONVEYER.

SPECIFICATION forming part of Letters Patent No. 786,643, dated April 4, 1905.

Application filed April 15, 1904. Serial No. 203,287.

To all whom it may concern:

Be it known that I, EDWIN A. HALLAM, a citizen of the United States, residing at Macon, in the county of Bibb and State of Georgia, have invented new and useful Improvements in Conveyers, of which the following is a specification.

This invention relates to conveyers particularly adapted for elevating and conveying logs. Primarily the invention resides in the trolley-carriage operating upon a cableway, said carriage carrying what may be termed the "drum for the receding rope," the "drum for the pulling-rope," and the "drum for the lifting-rope," said drums being operatively connected together.

The invention further aims to provide the carriage with a suitable brake for holding the carriage stationary, if desired, and to further provide means to permit of the receding drum operating in either direction when occasion requires, and said means is further adapted to lock the receding, lifting, and pulling rope drums together to prevent the movement thereof. The invention further aims to provide a new and novel form of conveyer which when set up will dispense with the separate gripping device employed in conveyers for logging purposes, said gripping device generally being arranged adjacent to the trolley-carriage, to further dispense with the cable between the gripping device and the trolley, and to further dispense with the ordinary outhaul-rope and its drum generally employed in conveyers for logging purposes.

The invention further aims to construct a conveyer device especially adapted for logging purposes which shall be simple in its construction, strong, durable, efficient in its use, and comparatively inexpensive to manufacture.

With the foregoing and other objects in view the invention consists of the novel combination and arrangement of parts hereinafter more specifically described, illustrated in the accompanying drawings, and particularly pointed out in the claims hereunto appended.

In describing the invention in detail reference is had to the accompanying drawings, forming a part of this specification, wherein

like reference characters denote corresponding parts throughout the several views, and in which—

Figure 1 is an elevation showing the general operation of the device. Fig. 2 is a side elevation of the trolley-carriage broken away. Fig. 3 is a sectional plan of the trolley-carriage on line 3 3 of Fig. 4. Fig. 4 is an end view of the trolley-carriage. Fig. 5 is a sectional detail view of the trolley-carriage. Fig. 6 is a side elevation of the trolley-carriage broken away, and Fig. 7 is a detail of one of the plates of the trolley-carriage.

The conveyer is shown as in use upon a cableway, although it will be evident with only slight or no modifications the conveyer might be used upon a rigid track instead of, as shown, a cable.

Referring to Fig. 1 of the drawings, a head-support is indicated by the reference character 1 and a tail-support by the reference character 2. These supports are in the form of upright posts and have the cableway 3 suitably connected thereto, as at 4 5. Any form of connecting means between the cableway 70 and supports 1 2 may be employed. In Fig. 1 of the drawings the reference character 6 denotes the trolley or conveyer carriage operating upon the cableway 3. The carriage 6 will be hereinafter more specifically described. 80 In Fig. 1 of the drawings the receding or outhaul rope is indicated by the reference character 7, the pulling or inhaul rope by the reference character 8, and the elevating or carrying rope is indicated by the reference character 9. The receding or outhaul rope 7 passes at its forward end over a pulley or sheave 10, suitably secured to the support 1, and at its outer end passes over the pulley or sheave 11, suitably connected to the support 2. The pulling or inhaul rope 8 passes over a pulley or sheave 12, suitably connected to the support 1. 13 denotes a winding-engine provided with the drum 14 for the outhaul-rope and the drum 15 for the inhaul rope or cable. The manner 95 of connecting the ropes or cables 7, 8, and 9 to the trolley or conveyer carriage and the manner in which the ropes or cables 7, 8, and 9 operate will be hereinafter referred to.

Referring to Figs. 2 to 6 of the drawings,

the trolley-carriage 6 consists of a pair of outer plates 16 17 and an intermediate plate 18, the said latter plate being arranged nearer the outer plate 17 and divides the carriage 5 into two compartments 19 and 20. Within the compartment 19 is arranged the drums for the ropes 7 8 9, and within the compartment 20 is arranged a train of gearing for the various drums, as well as a ratchet mechanism 10 for the receding-rope drum. The intermediate plate 18 and side plate 16 are of greater height than the outer plate 17 and at their upper ends converge inwardly toward each other, as at 21, and then extend upwardly 15 in a vertical manner, as at 22. The upper end of the outer plate 17 is bent inwardly, so as to engage the portion 21 of the intermediate plate 18, and the said plates 16, 17, and 18 are bolted together through the medium of suitable holdfast devices in the form of elongated bolts, as at 23 24, the bolts extending through the upper portions of the plates 16, 17, and 18. Between the plates 16 and 18, near their upper ends, is arranged a brace-block, preferably of wood, as indicated by the reference character 25, and through said block extends the bolts 23 and 24. Between the plates 17 and 18, at their upper ends, is arranged a brace-block 26, preferably of wood, and through 20 said block extends the bolts 24. It may be stated that any number of holdfast devices, such as the bolts 23 and 24, can be employed.

Journaled in the top of the carriage 6 between the portions 22 of the plates 16 and 18 35 and at each end of the carriage 6 is a trolley-wheel 27, traveling upon the cable 3. The carriage 6 when mounted in position is suspended upon the cable 3, as shown in Fig. 4. A suitable frictional braking means is employed 40 for retaining the trolley in any position desired, and said braking means consists of a pair of rollers 28, secured between the portions 22 of the plates 16 18 and above the cable 3. A brake-block 29 is interposed between the rollers 28 and arranged above the cable 3. A cam 30 is arranged below the rollers 28, block 29, and cable 3. The cam 30 is pivoted in the keeper 31, secured to the brace-block 25, the latter being recessed for 45 such purpose, as at 32. The braking means is operated by moving the cam 30 in such a manner so as to cause the clamping of the cable 3 between the rollers 28, block 29, and cam 30. The cam 30 is of such weight that 50 it will return to its non-braking position by gravity, and said cam 30 is operated through the medium of an outwardly-extending protuberance 33, projecting through a curved slot 34 in the plate 16 and connected to an operating-rope 35, which travels between a pair of guide and friction rollers 36, secured to the outer face of the plate 16. Suitable means can be employed for protecting the rollers 36.

65 The reference character 37 denotes the drum

for the receding rope 7, one end of said rope 7 being fixedly secured to said drum 37, and said rope 7 is adapted to wind upon and unwind off said drum 37. The drum 37 is fixed upon a shaft 38, which is journaled at its ends in the plates 16 and 17. The length of the drum 37 is such that it extends within the intermediate plate 18, a suitable opening 39 being provided for such purpose. That end of the drum which extends in the opening 39 70 has secured to it a gear-wheel 40, which in turn has secured thereto a ratchet-wheel 41. The ratchet-wheel 41 is adapted to be engaged by a pawl 42, so as to prevent the drum 41 turning in both directions as long as said pawl 42 engages with the ratchet 41. The pawl 42 is pivotally secured to the inner face of the plate 17, as at 43, and has its outer end somewhat elongated, as at 44. Said end 44 of the pawl 42 is adapted to be engaged by an eccentric 45, so as to disengage said pawl 42 from the ratchet 41. The eccentric 45 is operated so as to move the pawl 42 from its engagement with the ratchet 41 through the medium of the rope 46, and said eccentric 45 is operated so 80 as to permit of the return of the pawl to engage with the ratchet 41 through the medium of a rope 47 passing over the pulley 48. The eccentric 45 is pivoted, as at 49, to the inner face of the plate 17 and has connected therewith a handle 50, to which are attached the ropes 46 and 47. It may be stated that the pulley 48 is secured to the inner face of the plate 17. The pawl 42 is normally retained in engagement with the ratchet 41 through 90 the action of a flat spring 51, secured to the inner face of the plate 17, as at 52.

The reference character 53 denotes the drum for the pulling or inhaul rope 8, said rope 8 having its end fixedly secured to the drum 53, 100 and said rope 8 is adapted to wind and unwind upon and off said drum 53. The drum 53 is of such length as to have one end extend in the plate 18, and for this purpose an opening 54 is provided. That end of the drum 53 110 which projects into the opening 54 has secured thereto a gear-wheel 55, and said gear-wheel 55 meshes with a pinion 56, which in turn meshes with the gear 40, carried by the drum 37. The pinion 56 is mounted in the compartment 20 and is journaled in the sliding bearing 57. (See Fig. 5.) The plate 18 is cut away, as at 58, to provide for one side of the bearing 57, and the plate 17 has secured to its inner face a guideway 59 for the other side of 120 the bearing 57. A yoke 60 is secured to the bearing 57 and carries an adjusting-screw 61, operating through the guide 62. By such a construction it is evident that the pinion 56 can be moved away from the gears 40 and 55, 125 so that when it is desired the drums 37 and 53 can be operated independently of each other.

The reference character 63, Fig. 3, denotes the drum for the lifting or carrying rope 9, said rope 9 having its end fixedly secured to 130

the drum 63, and said rope 9 is adapted to wind and unwind upon and off said drum 63. The drum 63 is of such length as to have one end extend in the plate 18, and for this purpose an opening 64, Fig. 3, is provided. That end of the drum 63 which projects into the opening 64 has secured thereto a gear-wheel 65, and said gear-wheel 65 meshes with the gear-wheel 55, so that when either the drum 53 or 63 is rotated the said drums 53 and 63 will be revolved simultaneously. The shafts 66 and 67 for the drums 53 and 63 are journaled in the plates 16 and 17.

The receding or outhaul rope 7 winds upon and off the drum 37 from the top and on its passage back to the drum 14 does not pass through the trolley or conveyer carriage 6, but at the side thereof, and for such purpose the guide-pulleys 68 are provided, the rope passing between the said pulleys. The pulling or inhaul rope 8 winds on and off the drum 53 at the top thereof, and the lifting or carrying rope winds on and off the drum 63 at the side thereof, and when the conveyer is employed for logging purposes the rope 9 carries on its free end the tongs 69. (See Fig. 1.)

The operation of the device is as follows: Assuming that the carriage has been pulled out to the position shown in Fig. 1 through the operation of the drum 14, the pawl 42 is shifted so as to be free of the ratchet 41. The drum 14 is further operated so as to unwind the rope of the drum 37, such action rotating the drum 37, which in turn will cause the operation of the drum 53, winding the pulling-rope thereon from the drum 15. The operation of the drum 53 will in turn operate the drum 63, throwing out the lifting or carrying rope to which is attached the tongs 69. Before the pawl 42 is moved out of engagement with the ratchet 41 the brake is thrown on, so as to retain the carriage stationary. After the tongs 69 have been connected to the object desired to be conveyed the brake is released and the pawl thrown into engagement with the ratchet. The drum 15 is operated, which causes the rotation of the drum 53, and the object is lifted, owing to the operation of the drum 63 through the medium of the drum 53. The continued operation of the drum 15 will cause the carriage to be moved to the position desired upon the trolley-wire 3. When the carriage arrives at the position desired, the brake is again placed into operation, the pawl released, the slack is taken up in the rope 7, the rope 8 slackened, and the object transported will be lowered by gravity.

Although the device is shown provided with the pinion 56, yet it is evident that said pinion can be dispensed with and the drums directly geared with each other. When the pinion 56 is dispensed with, a reversal of the ropes on the lower drums will be necessary.

It is thought that the many advantages of a conveyer constructed in accordance with the

foregoing description can be readily understood, and it will furthermore be evident that changes, variations, and modifications can be resorted to without departing from the spirit of my invention or sacrificing any of its advantages, and I therefore do not wish to restrict myself to the details of construction hereinbefore described and set forth in the annexed drawings, but reserve the right to make such changes, variations, and modifications as come properly within the scope of the protection prayed.

Having thus fully described my invention, what I claim as new, and desire to secure by Letters Patent, is—

1. A conveyer comprising a traveling carriage, a receding-rope drum journaled therein, a pulling-rope drum journaled therein, a lifting-rope drum journaled therein, means for gearing the drums together, means carried by the carriage for locking the receding drum, thereby preventing the operation of the other drums thereof, releasing means carried by the carriage for said locking means, and a braking means carried by the carriage for retaining it stationary.

2. A conveyer comprising a traveling carriage, a receding-rope drum journaled therein, a pulling-rope drum journaled therein, a lifting-rope drum journaled therein, means carried by the carriage for locking the receding drum, thereby preventing the operation of the other drums thereof, releasing means carried by the carriage for said locking means, a braking means carried by the carriage for retaining it stationary, a rope having one end connected to said receding drum, a rope having one end connected to said pulling-drum, and a rope having one end connected to said lifting-drum.

3. In a conveyer device, in combination a separate pulling-rope, a carriage, a separate receding rope, a separate lifting-rope, and a separate winding-drum for each of said ropes carried by said carriage.

4. In a conveyer device, in combination a pulling-rope, a carriage, a receding rope, a lifting-rope, a winding-drum for each of said ropes carried by said carriage, and a braking means for said carriage carried thereby.

5. In a conveyer device, in combination a separate pulling-rope, a carriage, a separate receding rope, a separate lifting-rope, a separate winding-drum for each of said ropes carried by said carriage, and means for gearing said drums together.

6. In a conveyer device, in combination a separate pulling-rope, a carriage, a separate receding rope, a separate lifting-rope, a separate winding-drum for each of said ropes carried by said carriage, means for gearing said drums together, and means supported by the carriage for locking said receding-rope drum, thereby preventing the operation of the other drums.

7. In a conveyer, the combination of a pulling-rope, a carriage, a receding rope, a lifting-rope, a winding-drum for each of said ropes, a gear connected to each of said drums, said 5 gears for the lifting - rope and pulling-rope drums meshing with each other, and means for operatively connecting the gear of the receding-rope drum with the gear of the pulling-rope drum.
10. In a conveyer, the combination of a pulling-rope, a carriage, a receding rope, a lifting-rope, a winding-drum for each of said ropes, a gear connected to each of said drums, said 10 gears for the lifting-rope and pulling-rope drums meshing with each other, and adjustable means for operatively connecting the gear of the receding-rope drum with the gear of the pulling-rope drum.
15. In a conveyer, the combination of a carriage, a revolute drum supported by the carriage, a separate receding rope winding upon said drum and having one end connected thereto, another revolute drum supported by 15 said carriage, a separate pulling-rope winding upon said last-mentioned drum and having one end fixed thereto, another drum supported by said carriage, said drums operatively connected together, and a separate lifting-rope winding upon said last-mentioned drum and 20 having one end fixed thereto.
20. In a conveyer, the combination of a carriage, a revolute drum supported by the carriage, a receding rope winding upon said drum and having one end connected thereto, another 25 revolute drum supported by said carriage, a pulling - rope winding upon said last - mentioned drum and having one end fixed thereto, another drum supported by said carriage, a lifting-rope winding upon said last-mentioned 30 drum and having one end fixed thereto, and a braking means for the carriage carried thereby.
25. In a conveyer, the combination of a carriage, a revolute drum supported by the carriage, a receding rope winding upon said drum and having one end connected thereto, another 35 revolute drum supported by said carriage, a pulling - rope winding upon said last - mentioned drum and having one end fixed thereto, another drum supported by said carriage, a lifting-rope winding upon said last-mentioned 40 drum and having one end fixed thereto, and a braking means for the carriage carried thereby.
30. In a conveyer, the combination of a carriage, a revolute drum supported by the carriage, a receding rope winding upon said drum and having one end connected thereto, another 45 revolute drum supported by said carriage, a pulling - rope winding upon said last - mentioned drum and having one end fixed thereto, another drum supported by said carriage, a lifting-rope winding upon said last-mentioned 50 drum and having one end fixed thereto, a gear connected to each of said drums, the gear of the pulling-rope drum meshing with the gear of the 55 lifting-rope drum, and means for operatively connecting the gear of the receding-rope drum with the gear of the pulling-rope drum.
35. In a conveyer, the combination of a carriage, a revolute drum supported by the carriage, a receding rope winding upon said drum and having one end connected thereto, another 60 revolute drum supported by said carriage, a pulling - rope winding upon said last - mentioned drum and having one end fixed thereto, another drum supported by said carriage, a lifting-rope winding upon said last-mentioned 65 drum and having one end fixed thereto, another drum supported by said carriage, a separate 70 lifting-rope winding upon said last-mentioned drum and having one end fixed thereto, a gear connected to each of said drums, the gear of the pulling-rope drum meshing with the gear of the lifting-rope drum, and adjustable means for operatively connecting the gear of the receding drum with the gear of the pulling-rope drum.
40. In a conveyer device, in combination a 75 separate pulling-rope, a carriage, a separate receding rope, a separate lifting-rope, a separate winding-drum for each of said ropes carried by said carriage, and a winding-engine connected with said pulling-rope and said receding rope.
45. In a conveyer device, in combination a 80 separate pulling-rope, a carriage, a separate receding rope, a separate lifting-rope, a separate winding-drum for each of said ropes carried by said carriage, a braking means for said carriage carried thereby, and a winding-engine connected with said pulling-rope and said receding rope.
50. In a conveyer device, in combination a 85 separate pulling-rope, a carriage, a separate receding rope, a separate lifting-rope, a separate winding-drum for each of said ropes carried by said carriage, a braking means for said carriage carried thereby, and a winding-engine connected with said pulling-rope and said receding rope.
55. In a conveyer device, in combination a 90 separate pulling-rope, a carriage, a separate receding rope, a separate lifting-rope, a separate winding-drum for each of said ropes carried by said carriage, means for gearing said drums together, and a winding-engine connected with said pulling-rope and said receding rope.
60. In a conveyer device, in combination a 95 separate pulling-rope, a carriage, a separate receding rope, a separate lifting-rope, a separate winding-drum for each of said ropes carried by said carriage, means for gearing said drums together, means supported by the carriage for locking said receding - rope drum, thereby preventing the other drums from 100 turning, and a winding-engine connected with said receding rope and said pulling-rope.
65. In a conveyer device, in combination a 105 separate pulling-rope, a carriage, a separate receding rope, a separate lifting-rope, a separate winding-drum for each of said ropes carried by said carriage, means for gearing said drums together, means supported by the carriage for locking said receding - rope drum, thereby preventing the other drums from 110 turning, and a winding-engine connected with said receding rope and said pulling-rope.
70. In a conveyer device, in combination a 115 separate pulling-rope, a carriage, a separate receding rope, a separate lifting-rope, a separate winding-drum for each of said ropes carried by said carriage, a winding - engine connected with said pulling-rope and said receding rope, and means for locking said receding drum, thereby preventing the turning of the other drums when the carriage is moving 120 toward the winding-engine.
75. In a conveyer device, in combination a 125 separate pulling-rope, a carriage, a separate receding rope, a separate lifting-rope, a separate winding-drum for each of said ropes carried by said carriage, a braking means for said carriage carried thereby, a winding - engine connected with said pulling-rope and said receding rope, and means for locking said receding drum, thereby preventing the turning of the other drums when the carriage is moving 130 toward the winding-engine.
80. In a conveyer device, in combination a 135 separate pulling-rope, a carriage, a separate receding rope, a separate lifting-rope, a separate winding-drum for each of said ropes carried by said carriage, a braking means for said carriage carried thereby, a winding - engine connected with said pulling-rope and said receding rope, and means for locking said receding drum, thereby preventing the turning of the other drums when the carriage is moving 140 toward the winding-engine.

receding rope, a separate lifting-rope, a separate winding-drum for each of said ropes carried by said carriage, and means for locking the receding-rope drum to arrest the movement thereof in one direction.

20. In a conveyer device, in combination a separate pulling-rope, a carriage, a separate receding rope, a separate lifting-rope, a separate winding-drum for each of said ropes carried by said carriage, means for locking the receding-rope drum to arrest the movement thereof in one direction, and means for disconnecting said locking means from the receding-rope drum.

21. In a conveyer device, in combination a separate pulling-rope, a carriage, a separate receding rope, a separate lifting-rope, a separate winding-drum for each of said ropes carried by said carriage, and means for pre-

venting the drums from turning while the carriage is traveling.

22. In a conveyer device, in combination a separate pulling-rope, a carriage, a separate receding rope, a separate lifting-rope, a separate winding-drum for each of said ropes carried by said carriage, means for preventing the drums from turning while the carriage is traveling, and means for throwing out of engagement said means to permit of the turning of the drums.

In testimony whereof I have hereunto set my hand in presence of two subscribing witnesses.

EDWIN A. HALLAM.
